CARTRIDGE BELT LINK MANUFACTURE

Petter Moinichen, Chicago, Ill., assignor, by
mesne assignments, to the United States
Government, as represented by the Secretary of
War and his successors in office

Application July 2, 1942, Serial No. 449,535

3 Claims.

(Cl. 59—6)

This invention relates to a method for forming ammunition belt links, to a progressive die which may be utilized in the manufacture of such links, and to a novel strip for "scrapless" formation of belt links in a progressive die.

Link-type ammunition belts comprise links formed of sheet metal bent to form coaxial spaced rings and a single ring complementary to the space between the coaxial rings arranged to interfit with coaxial rings of an adjacent link to provide a cylinder for the reception of cartridges which serve as pintles for the links.

The manufacture of ammunition belt links as heretofore proposed involving the use of heretofore known progressive dies through which a strip of material is fed and formed at successive stations into a completed link has required the use of a strip wider than the width of the finished link to provide continuous bands of material at each side of the blanks cut in the strip to which the link blanks remain connected for movement through the die with the strip. These side bands are also necessary to cooperate with a spring carrier plate forming a necessary part of such dies, which lifts the partly formed link blanks out of engagement with successive forming members of the progressive die to permit forward movement of the blanks through the die as a unit with the strip.

Such progressive dies have resulted in a large percentage of waste of the strip material fed to the dies, due to the necessity for side strips for engagement with the spring stripper, and also to the necessity for excessive longitudinal spacing of successive link blanks, due in part to the manner in which the link blanks were secured to the side strips, and in part to the manner of cutting.

The forming of the links in such known dies is effected by means of a series of fixed forming members ground to close tolerances complementary to spring-mounted reciprocating forming members. In the operation of these heretofore known progressive dies, it has been found that an increase in the rate of operation above a definite value resulted in excessive strain on the spring members, e. g., of the spring carrier plate and of spring-mounted die members so that early failure resulted.

It is an object of the present invention to provide an improved method of forming a belt link from a strip of material substantially equal in width to the width of the final link, and with the formation of only a minimum of waste.

It is a further object to provide a method of forming belt links whereby the links may be formed at an exceptionally high rate without excessive deterioration of the die.

It is another object of the invention to pro-

vide an improved progressive die for forming belt links from a strip of material of width substantially equal to the width of the finished link, and with the formation of only a minimum of waste material.

It is still another object to provide a progressive die which is capable of operation at high speed to form a belt link.

It is a still further object to provide a novel strip comprising a series of partially formed link blanks connected together for substantially "scrapless" formation of belt links in a progressive die.

In accordance with the method of the present invention, a continuous strip of material equal in width to the width of the finished link is fed as a unit to progressive stations of a die, and is cut at successive stations to define blanks comprising parallel strip members to be bent into coaxial rings, a single strip member to be bent to form a single ring, and a shoulder portion connecting the strip members, leaving a connecting portion between the link blank and the remainder of the strip. The link blank is moved by the connecting portion to forming stations, the connecting portion is then cut, and the link blank is bent to form a link.

A progressive die according to my invention suitable for use in connection with the practice of the method may comprise a stationary die member, a movable die member co-operating with the stationary member to provide cutting and shaping members, and a feeder to supply to the die a continuous strip of material in successive uniform lengths. As more fully described hereinafter, the progressive die may comprise a shear to cut the strip on lines defining edges of parallel strip members of a link blank which are to be bent to form coaxial rings and to define the edges of a single strip member of a link blank, which is to be bent to form a single ring, the shear being constructed to leave uncut a connecting portion between a link blank and the stock strip. The die also comprises a shear to which the partly formed link blank is fed by movement of the strip to sever the connecting portion between the link blank and the remainder of the strip, and members co-operating to bend the link blank to form the parallel strip members of the blank into coaxial rings, and the single strip member into a single ring.

Further objects and advantages will in part be described hereinafter, and in part will be apparent from the following description taken in connection with the accompanying drawings forming part of the disclosure of the present invention.

Other objects and advantages of the invention will appear from a consideration of the following detailed specification.

Accordingly, for a more complete understanding of the invention, reference is made to the accompanying drawings, in which

Figure 1 is a plan view of the stationary member of the progressive die of my invention showing the successive stations of the die with a strip in place, and indicating in heavy lines the cuts made at each station.

Fig. 2 is an elevational view of the die showing the die of my invention, with the movable upper die member of the progressive die in its lower-most position to cut and form the strip material.

Fig. 3 is a perspective of a strip as acted on by the die member, and illustrates the cuts and bends formed in making a belt link.

Figure 4 is an end elevational view showing the loop-forming elements of the progressive die of my invention in section on line IV—IV Figure 2.

Figure 5 is a section on line V—V Figure 4.

Fig. 6 is a perspective view of a completed belt link formed by the progressive die shown in Figs. 1 to 4.

A progressive die according to my invention (see particularly Figs. 1 and 2) comprises a stationary lower member 10 in which guide posts 11 are mounted, a vertically reciprocable upper member 12 provided with guide sleeves 13 fitting over posts 11, and a feeding device 14' of any known or suitable type, for supplying to the die successive lengths of a stock strip 14 of material for formation into a belt link.

In the following description of the die, various portions of the die will be referred to as stations and will be described separately, but it is to be understood that in the operation of the die each of the stations performs its function at every cycle of the die member, the progressive formation of the belt link being due to progression of partially formed link blank portions of the strip to successive portions of the die where they are subject to further forming steps. Similar elements of each of the blanks of the series of partially formed link blanks in the die will be referred to by the same number, but will be distinguished by a superscript. That is, all elements of the first link blank will be given plain numbers, all elements of the second link blank will be given prime numbers, and so on.

Suitable feeding mechanism, as for example feeding mechanism such as shown in Dickerman Patent No. 1,968,479, dated July 31, 1934, may be employed for feeding in a strip of stock 14 between the fixed positioning guide 16 at one side of the strip and a guide 18 at the other side of the strip comprising strip-engaging members 20 which are pressed against the edge of the strip 14 to hold it firmly in place by means of a leaf spring 21 engaging the ends of the members. These guides direct the strip accurately to the first station of the die. Such a feeding mechanism is represented diagrammatically in Figure 2 and is designated by the numeral 14'.

The first station of the die comprises a stationary guide member 22, and spring-pressed guide members 23 at the sides of the strip to hold the strip firmly in position, and a punch member 24 mounted in the vertically reciprocable member 12, cooperating with a shearing edge 26 in the stationary member 10 to punch a hole 28 (see Fig. 3) in the strip 14 which is shaped and located to define the end of a single strip member 30 of a first link blank 32 to be cut from the strip and to form the inner edge of the shoulder of a second link blank 34. As shown in Fig. 2, the punch 24

passes through a hole 36 in a stripper plate 38 of which is secured to the stationary member 10 of the die and which holds the strip down when the punch is raised by movement of the die member 12. The material punched from the stock strip 14 falls through slug hole 40 in the stationary member 10 of the die, and passes to waste.

The second station of the die comprises a positioning pin 42 having the cross-sectional shape of the hole 28 and which projects through the hole 28' punched in the strip 14 at the first station to locate the strip exactly for a shearing operation. Shearing members 44, 46, and 48, mounted in vertically reciprocable member 12 of the die, comprise cutting edges 50, 52, and 54 set at an angle to the horizontal with their left-hand ends, i. e., the end farthest in the direction of movement of the strip 14 through the die higher than their right-hand ends. The cutting edge 50 co-operates with shearing edges 56 of the stationary die member 10 to cut the strip 14 on lines defining a portion of the outer edges of a single strip member 30' of the second link blank 34, and a portion of the inner edges of parallel strip members 58'' and 60'' of a third link blank 62 to be cut from the strip. The cutting edges 52 and 54 co-operate with shearing edges 64 and 66 on stationary die member 10 to cut the strip on lines defining the ends of parallel strip members 58'' and 60'' of the third link blank 62 to be cut from the strip. As shown particularly in Figs. 1 and 3, this cutting leaves two unsevered connecting portions between the parallel strip members 58'' and 60'' of the third link blank 62 and the single strip member 30' of the second blank 34 by which the third link blank 62 remains connected through the second link blank 34 to the strip 14 so that the partially formed link blank remains a part of the strip 14 for movement with the strip to subsequent stations.

As shown in Fig. 2, the shearing members 44, 46 and 48 pass through openings 67, 68 and 69 in the stripper 38 which holds the strip in place when the shearing members are raised by movement of the die member 12.

The third station of the progressive die comprises shearing members 72 mounted on the vertically reciprocable member 12 of the die co-operating with the shearing member 74 on the stationary member 10 of the die to form the neck of the single strip member 30'' and to form the shoulders of the blank 62. The shearing members 72 pass through holes 75 in the stripper 38. The material punched from the strip falls through slug holes 73.

It is particularly to be noted that by cutting the strip 14 to form the ends of the parallel strip members of a link blank in one stage and cutting the strip to form the neck and the shoulder in a second stage, it is possible to remove thin intervening portions of metal between adjacent link blanks which could not be removed by a single punch of the die because of the impossibility of forming a die with a sufficiently thin face to remove these segments satisfactorily.

The third station also comprises a bending form 76 which is slidably mounted in the vertically reciprocable die member 12. Springs 77 presses the form 76 downwardly in the die member 12, the downward movement being limited by engagement of the enlarged head of the form 76 with shoulder 78 of the die member 12. The form 76 co-operates with an independently actuated forming member 79 mounted on the stationary

die member 10 and having a concave surface co-operating with the convex surface of the bending form 76 to bend up the end of the single strip member 30" to provide clearance between the end of the single strip member 30" and the inside of the shoulder of a fourth link blank 80 for a subsequent operation. As shown in Figs. 1 and 2, forming member 79 is fixed on shaft 82 journalled in the stationary die member 10 and is operated to effect bending by an arm 84 keyed to shaft 82 which is pushed down to actuate the forming member 79 by pin 85 fixed in the movable member 12 of the die.

A fourth station comprises a positioning pin 86 having the cross-sectional shape of the hole 28 and co-operating with the hole 28''' to position the strip accurately for bending. Bending members 87 and 88 are slidably mounted in die member 12, and are pressed downwardly by springs 89 and 90, the downward movement being limited by engagement of the enlarged heads of the members 87 and 88 with shoulders 91 and 92 of die member 12. The members 87 and 88 co-operate with bending members 94 and 96 to bend up the ends of the parallel strip members 58''' and 60''' of a fifth link blank 95. As shown in Fig. 2, bending members 94 and 96 are fixed on shafts 98 and 100 journalled in the stationary die member 10 and are operated to effect bending by arms 102 and 104 keyed to the shafts 98 and 100 which are pushed down by pins 106 and 108 set in the movable member 12 of the die.

At a fifth station (see particularly Figs. 1 and 2) there is provided a holding and bending member 109 which is slidably mounted in the movable member 12 of the die and is pressed downwardly by spring 110, the downward movement being limited by engagement of the enlarged head of the member 109 with the shoulder 111 in die member 12, and a bending and shearing member 113 which is fixed on the shaft 114 journalled in the stationary member 10 of the die. The member 109 is formed at its lower end to provide a strip-engaging portion 112 having a curved surface around which the single strip member is to be bent. The member 109 projects down from the die member 12 so that the portion 112 engages the strip 14 at an early point in the descent of die member 12. After the portions 112 engage the strip, further downward movement of the member 109 ceases, and spring 110 is compressed, thus applying pressure to hold the strip firmly in place. The shearing member 113 is rotated by means of an arm 116 keyed to the shaft 114 which is pushed down by operating pin or cam 117 which is set in the vertically reciprocable member 12 of the die. The cam 117 is provided with a shoulder 118 to force the shearing and bending member 113 upward. Member 113 bends the single strip member 30''' upwards around the curve of the member 109 and severs the connecting portions between the single strip member 30''' of fifth link blank 95 and the parallel strip members 58' and 60' of a sixth link blank 119 at an early point in the descent of the member 12 so that the parallel strip members 58' and 60' are free to be bent into rings.

The fifth station also comprises (see Figs. 1, 2, 4 and 5) a lower forming member 120 mounted on the stationary die member 10 having spaced depressions 122 and 124 corresponding to the exterior of the lower half of a belt link of the class described, i. e., the left-hand depression 122, and the portion of the right-hand depression 124 which will receive the longer parallel strip mem-

bers 60' form substantially half cylinders, while the portion of the right-hand depression 124 which will receive the shorter parallel strip member 58', is in the form of half a truncated cone joined to a short half-cylinder portion. As shown in Fig. 1, projections 126, which may be spring-mounted pins for engaging the interior of the shoulder of link blank 119 to hold it in position during the forming operations, may be provided at the center portion between the depressions 122 and 124.

Upper forming member 128 is similar to the lower forming member 120 and cooperates with it to complete the cylinders, and cylinder and truncated cones of the lower member.

Arbors 130 and 132 operated by mechanism described hereinafter are movable in raised position out over the depressions 122 and 124 and the partially formed link blank 119 and cooperate with the lower and upper forming members 120 and 128 to complete bending of the blank to form a belt link 119.

A spreader 134 is mounted on the vertically reciprocable member 12 and adapted to maintain the parallel strip members 58' and 60' and the rings formed therefrom in definite spaced relation. The spreader comprises two fingers 136 which extend down to engage a reduced portion 138 of the right-hand arbor 132 at an early point in the descent of the die member 12, but at a time after the blank 119 has been moved to position above member 120, and holds both the right-hand arbor 132 and the blank 119 firmly in place when the connecting portions between parallel strip members 58' and 60' and single strip member 30''' are severed, and to maintain them in place while the upper and lower members 120 and 128 are moved together to form the link.

As shown in Figs. 4 and 5, mechanism for moving the arbors 130 and 132 comprises a member 140 having holes 142 and 144 in which the arbors are mounted, the arbors being held firmly in member 140 by means of set screws 146. The arbor-supporting member 140 is mounted for horizontal movement to and from a position in which the arbors are directly above the path of the strip between the parallel side guides 148. Retaining members 150 are secured to the upper edges of the side guides and cooperate with shoulders 152 of the arbor-supporting member 140 to retain the arbor-supporting member 140 in the channel formed by the guides 148. The bottom of the channel defined by the parallel side guides 148 comprises a fixed portion 154 and a vertically reciprocable portion 156 which is pressed upward by the springs 158, and is movable from a position in which its upper surface is substantially in line with the fixed member 154 to a position substantially below the fixed member in which the edge 160 of the fixed member 154 forms a shoulder for engagement with the shoulder 162 of the arbor-supporting member 140 to retain the arbor-supporting member against lateral movement when the arbors are pushed down in forming a belt link.

The arbor-supporting member 140 is operated by means of a stiff link 164 pivotally connected at one end through pin 166 to the upper portion of the arbor-supporting member 140 and pivotally connected at the other end through pin 168 to a pin 169 which is vertically reciprocable in the movable die member 12, and which is pressed downwardly by the spring 170. A shoulder 171 is provided on the pin to engage the shoulder 172 in the hole 173 in which the pin 169

is mounted, to limit the downward movement of the pin. In order to control the pressure of the spring 170, opposing springs 174 are provided in the holes 175 in member 12, which act to balance the downward pressure of spring 170, through shoulder bolts 176 which are slidable in holes 175 and are adjustable in projections 177 at the side of pin 169.

The link 164 and pin 169 are constructed and arranged so that when the movable member 12 of the die is in raised position, the link 164 raises the arbor-supporting member 140 and slides it to a position in which the arbors 130 and 132 are out of line with the path of the bent-up portion 30^v of blank 119 and when the movable die member 12 is lowered, the link 164 forces the arbor-supporting member 140 to a position above the strip 14 at a time when the bent-up end of the single strip member 30^v of the partially formed link blank 119 has passed the cylindrical arbor 130. When the arbors are in position above the strip, further downward movement of the movable die member 12 moves a slidably mounted bearing block 178 into engagement with the upper edge of the arbor-supporting member 140. As shown in Fig. 4, bearing block 178 is slidably connected to die member 12 by a shoulder bolt 179 projecting through a hole 180 in die member 12 permitting downward movement of the member 178, limited by the engagement of the shoulder of the bolt with the upper surface of die member 12. A spring 181 is mounted in an enlarged portion of the hole 180 and holds the member 178 in its lowermost position until it engages the arbor-supporting member 140 and resiliently presses it down to bend the link blank. As pointed out hereinbefore, movement of the arbor-supporting member 140 downwardly brings the shoulder 162 of the arbor-supporting member and the shoulder 160 of the stationary member 154 into cooperative engagement to prevent lateral movement of the arbor-supporting member 140 and arbors 130 and 132. The upper forming member 128 engages the partially bent strip members 30^v, 58^v and 60^v of the link blank 119 and together with the arbors 130 and 132 and the lower forming members 122 and 124 complete the bending of the link blank to form a completed belt link, (see Fig. 6).

To summarize the action of the fifth station: Bent-up portion of the single strip member 30^v of a link blank 119 is moved by feeding of the strip 14 to a position past the position of the cylindrical arbor 130. The arbors 130 and 132 are then moved to a position above the link blank by means of the link 164, and are engaged by the fingers 136 of spreader 134. Shoulder 118 of the cam 117 moves downwardly against the arm 116 and rotates the shear member 113 to bend up the single strip member 30^{'''} and sever the connecting portions between the single strip member 30^{'''} of link blank 95 and the parallel strip members 58^v and 60^v of link blank 119 which latter is held in place by the spreader fingers 136 and the arbors 130 and 132. Bearing member 178 of the upper die member 12 engages the upper edge of the arbor-supporting member 140 to force the arbors 130 and 132 downwardly to effect bending of the strip members 30^v, 58^v and 60^v of the link blank 119, and the upper forming member 128 engages the partially bent strip members to cooperate with the arbors 130 and 132 and the lower forming member 120 to complete the bending of the link blank.

When the reciprocable die member 12 is raised, the forming portion 128 is moved out of engagement with the completed belt link, the arbor-supporting member 140 is raised by the link 164 carrying the completed link with it away from the lower forming member 120, and the arbor-supporting member 140 is then moved to a position out of line with the path of the strip. Stripping of the link from the arbors 130 and 132 is effected by means of the plate 182 which is provided with slots 184 projecting around the arbors 130 and 132 to strip the link blank from the arbors when the arbor-supporting member 140 and arbors are moved away from the path of the strip as the reciprocable die member is raised.

As can be seen from the above description, a strip 14 of material of width corresponding to the width of the link is fed in successive uniform lengths corresponding to the stations of the die, e. g., the distance between the punch 24 and the positioning pin 42 of the die. As shown in Figs. 1, 2, and 3, strip 14 is punched at the first station to form a hole 28 which serves for positioning the strip 14 for succeeding operations. The hole 28 is shaped and located to define the end of a single strip member 30 of a first link blank 32 and the interior of the shoulder of a second link blank 34. At a second station the strip 14 is cut along lines defining a portion of the outer edges of the single strip member 30', these lines also serving to define a portion of the inner edges of the parallel strip members 58^v and 60^v of a third link blank 62. At this station also the blank 62 is cut to form the ends of the parallel strip members 58^v and 60^v of the third link blank, leaving unsevered connecting portions by which the third link blank 62 is connected to the strip 14 through the second link blank 34. By means of these connecting portions, the partially formed link blank 62 may be moved to successive operations as a part of the strip 14.

At a third station, the strip is cut to form the neck and shoulders of the third link blank 62, and the single strip member 30^v of the third link blank 62 is bent up to provide clearance for subsequent steps.

At a fourth station, the ends of the parallel strip members 58^{'''} and 60^{'''} of a fifth blank 95 are bent up.

At a fifth station, a sixth link 119 has been moved by movement of the strip 14 to a position in which it can be formed into a link. The connecting portions between the blank 119 and the strip 14 are cut, and the blank is then bent to form a completed belt link (Fig. 6).

It should be understood that the steps hereinabove described comprise an invention applicable to the manufacture of links other than those shown in said copending application. The forming steps which are hereinabove disclosed constitute an appreciable percentage decrease in the steps heretofore necessary in forming cartridge links of the character described, and in this fact alone and disregarding all of the other advantages in the hereinabove described procedure, and the dies and mandrels for carrying it out, constitutes a valuable contribution in the saving of material for the dies.

Further modifications of this invention will be apparent to those skilled in the art. For example, the sequence of the various cutting operations might be changed, or the location of the connecting portions altered, or the cutting

steps of the several stations may be rearranged to effect the cutting in fewer or in a greater number of stations, and it is desired, in fact, that my invention be limited only by the scope of the appended claims.

Therefore, it is not intended that the description heretofore given of the invention and/or the showing thereof set forth in the drawings is limiting in any respect of the monopoly claimed. It is on the contrary intended that all claims hereinafter allowed, whether made initially or to be added (assuming that they are properly supportable by the drawings and/or specification and/or claims originally made herein), shall be the measure of the scope of the invention herein set forth. Accordingly, and with the foregoing in mind, what is claimed as new and is desired to be secured by Letters Patent is (remembering that claims broader than those now included may hereafter be found properly includable herein):

1. In a progressive die comprising a stationary die member, a movable die member co-operating therewith to provide a series of cutting and shaping devices and a feeder for supplying to the die a continuous strip in successive uniform lengths for formation of an ammunition belt link of the class described from a continuous strip of metal of width substantially corresponding to the width of the link and with a minimum of waste, a punch constructed to form a hole in the strip shaped and located to define in the strip the end of a single strip member of a link blank which is to be bent to form a single ring of a belt link, said punch also forming the inner edges of the shoulder of an adjacent link blank, a shear to cut the strip on lines defining a portion of the inner edges of parallel strip members of a link blank which are to be bent to form paired coaxial cartridge-receiving rings, and to form the ends of these parallel strip members, said lines defining a portion of the outer edge of a single strip member of a link blank, leaving a connecting portion between the parallel strip members of one link blank and the single strip member of an adjacent link blank, a shear to cut the strip to form shoulders and neck portion of a link blank, forming members movable with the movable portion of the die and separately actuated members co-operating with said forming members to bend up the ends of the single and parallel strip members, a shear to cut the connecting portion between the single strip member of a blank and the parallel strip members of an adjacent blank, and two arbors operable to be moved out over the strip member when the strip member is positioned above the lower die portion, said arbors co-operating with die portions to bend the link blank to form the parallel strip members into coaxial rings, and a single strip member into a single ring to form a cartridge belt link.

2. In a progressive die comprising a stationary die member, a movable die member co-operating therewith to provide a series of cutting and shaping stations, and a feeding device for supplying to successive stations of the die a continuous strip in successive uniform lengths corresponding to the lengths of the stations for formation of an ammunition belt link of the class described from a continuous strip of metal of width substantially corresponding to the width of the link and with a minimum of waste, a first station comprising a punch constructed to form a hole

in the strip shaped and located to define in the strip the end of a single strip member of a link blank which is to be bent to form a single ring of a belt link, said punch also forming the inner edges of the shoulder of a second link blank, a second station comprising a shear to cut the strip on lines defining a portion of the inner edges of parallel strip members of a link blank which are to be bent to form paired coaxial cartridge-receiving rings, and to form the ends of these parallel strip members, said lines defining a portion of the outer edge of a single strip member of a link blank, leaving a connecting portion between the parallel strip members of one link blank and the single strip member of an adjacent link blank, a third station comprising a shear to cut the strip to form shoulders and neck portion of a link blank, a forming member movable with the movable portion of the die and an actuated member co-operating with said forming members to bend up the ends of the single strip members, a fourth station comprising forming means movable with the movable portion of the die and actuated means cooperating with said forming means to bend up the ends of the parallel strip members, and a fifth station comprising upper and lower die portions including a shear to cut the connecting portion between the single strip member of a blank and the parallel strip members of an adjacent blank, and two arbors operable to be moved out over the strip member when the strip member is positioned above the lower die portion, said arbors co-operating with die portions to bend the link blank to form the parallel strip members into coaxial rings, and a single strip member into a single ring to form a cartridge belt link.

3. In a progressive die comprising a stationary die member, a movable die member co-operating therewith to provide a series of cutting and shaping devices and a feeder for supplying to the die a continuous strip in successive uniform lengths for formation of an ammunition belt link of the class described from a continuous strip of metal of width substantially corresponding to the width of the link and with a minimum of waste, a punch constructed to form a hole in the strip shaped and located to define in the strip the end of a single strip member of a link blank which is to be bent to form a single ring of a belt link, said punch also forming the inner edges of the shoulder of an adjacent link blank, a shear to cut the strip on lines defining a portion of the inner edges of parallel strip members of a link blank which are to be bent to form paired coaxial cartridge-receiving rings, and to form the ends of these parallel strip members, said lines defining a portion of the outer edge of a single strip member of a link blank, leaving a connecting portion between the parallel strip members of one link blank and the single strip member of an adjacent link blank, a shear to cut the strip to form shoulders and neck portion of a link blank, forming members movable with the movable portion of the die and separately actuated members co-operating with said forming members to bend up the ends of the single and parallel strip members, a shear to cut the connecting portion between the single strip member of a blank and the parallel strip members of an adjacent blank, and means for bending the link blank to form the parallel strip members into coaxial rings and the single strip member into a single ring.

PETTER MOINICHEN.
